ELEVATED TANK

Harry E. Lindberg, Pittsburgh, Pa., assignor to
 Pittsburgh-Des Moines Company, Pittsburgh,
 Pa., a corporation of Pennsylvania

Application March 23, 1951, Serial No. 217,170

8 Claims. (Cl. 220—1)

1

This invention relates to elevated tanks and an object thereof is to produce an elevated tank of novel design and novel construction.

Elevated tanks usually comprise a tank shell and means for supporting such shell a desired distance above the ground; such supporting means is commonly referred to as the "tower," although it may comprise a number of column-like members which may or may not be interconnected by diagonal bracing members. These column-like members may extend vertically or incline either inwardly or outwardly from their foundations to the tank shell.

In the tank of this invention, the column-like members converge from their foundations to the tank shell which may be of varied design as long as it is symmetrical about its vertical center line or axis.

The column-like members are preferably cylindrical and straight and may be of any desired number provided there are at least three.

The bottom portions or bases of these column-like members are secured to foundation members which are preferably equally spaced from the vertical center line of the tank shell when such line is extended to the ground.

In the drawings which accompany and form part of this application:

Figure 1 is an elevational view of a tank embodying this invention;

Fig. 2 is a view partially in section and partially in elevation on an enlarged scale of the tank shell, upper portions of the three column-like tower members and the internal framing means. This view is taken on line II—II of Fig. 3;

Fig. 3 is a view partially in section and partially in plan and is taken on line III—III of Fig. 2;

Fig. 4 is a greatly enlarged fragmentary view taken on line IV—IV of Fig. 5;

Fig. 5 is a view partially in plan and partially in section and is taken on line V—V of Fig. 4;

Fig. 6 is a view partially in section and partially in elevation and is taken on line VI—VI of Fig. 4;

Fig. 7 is a view similar to Fig. 2 but on a reduced scale and illustrates a modified form of elevated tank embodying this invention and is taken on line VII—VII of Fig. 8; and

Fig. 8 is a view partially in section and partially in plan and is taken on the line VIII—VIII of Fig. 7.

The tank shell 10 which is shown as a hollow sphere is supported by three hollow cylindrical

2

column-like legs 11. Columns 11 are secured to metal base members 12 which in turn are secured to concrete foundation members or piers 13.

The tank shell 10 can be of any desired form so long as it is symmetrical about its vertical center line. Columns 11 while they are preferably cylindrical and tubular as shown they can be of any desired structural shape. They may also be of any desired number, but not less than three.

Base members 12 are preferably equally spaced from the vertical center line of the tank shell when such center line is extended to the ground.

Column-like members 11 extend through openings provided for that purpose in tank shell 10 and are connected to a vertical post 14. The vertical center line or longitudinal axis of post 14 preferably coincides with the vertical center line of the tank shell.

Members 11 which incline from their base members 12 to a point in the vertical center line of the tank shell are sealed, preferably by weld metal to the walls of the openings in the tank shell through which they project. They are secured preferably by welding, to vertical post 14.

The axes of column-like members 11 as above pointed out intersect one another in such vertical center line; such point is numbered 15. Point 15 is preferably at the same level as resultant of horizontal forces on the tank, usually wind forces.

In order that the wind pressure load on the tank shell and the weight of the tank shell and its contents are transferred to column-like members 11, I provide a series of frame members 16, preferably of I or H beam section, which are connected to one end of center post 14 and to the tank shell 10 adjacent the extreme horizontal dimension of the shell.

In Figures 2 and 3, I show five such frames which are connected to post 14 adjacent its top, and to the tank shell at equally spaced portions adjacent such extreme dimension of the shell by means of gusset plates 17 which are secured to the tank shell.

Horizontal framing members 18 which are equal in number to frame members 16 are connected to members 16 within gusset plates 17 as shown in Figs. 2 and 4. Members 18 are also preferably of H or I beam section (although they may be tubular or of any other desired section) and are connected, preferably by welding, to framing members 16 between gusset plates 17.

3

They are connected, also preferably by welding, to center post 14 (Figs. 4 and 5).

For the purpose of carrying the load in framing members 18 across center post 14, I preferably provide a plate-like diaphragm 19 which is aligned with the webs 18a of framing members 18. I reinforce diaphragm 19 by means of stiffening members 20 which are aligned with the flanges 18b of members 18. These stiffening members are joined together within cylindrical posts 14 by weld metal 20a as shown in Figs. 3 and 4.

A diaphragm 21 is welded in place within the upper portion of center column 14 and is stiffened by means of upper and lower stiffening members numbered 22 and 23 respectively. These members are welded to diaphragm 21 and to the inner surface of post 14.

In the modification shown in Figs. 7 and 8, instead of five frames which are located in the upper half of the tank shell, I disclose but three frames (see Fig. 8). These three frames as shown in Fig. 7 are connected to center post 14 and located in the lower part of the tank instead of in the upper part. These frames also include a diaphragm 19 and stiffening member 20 at the upper end of shortened post 14 and similar diaphragm and stiffening members at the lower end of post 14.

The ends of center post 14 are spaced from the tank shell. The lower half of center post 14 is fixed in position by column-like tower members 11 which are secured to center post 14 and are sealed to the walls of the openings in the tank shell bottom by welding.

The height of the supporting tower will depend somewhat upon the water pressure desired in the system of which the tank forms a part.

Since clearance is provided between the upper end of center post 14 and the tank shell, the upper half of the tank shell is free to expand when heated by the sun. The lower part of the center post 14 as well as the upper ends of column-like members 11 and most of the framing will be immersed within the liquid contents of the tank shell and therefore will not be subject to rapid fluctuations in temperature.

The spread of the column-like members 11 will depend upon their height, and size of the tank shell and the inclination desired for best economy in design of members 11 and in design of piers 13.

The absence of diagonal bracing members gives the tank of this invention a novel and striking appearance.

What I claim is:

1. An elevated tank and the support therefor, comprising a tank shell symmetrical about its center line; a vertically extending center post within said shell, with the axis thereof coincident with said center line, and with the upper end thereof spaced from and free of the upper portion of said shell; a series of frames spaced at equal intervals around said center post, and each comprising an inclined member and a substantially horizontal member arranged in pairs, with the members of each pair having their inner ends secured to said post at spaced points longitudinally thereof, and their outer ends connected to said shell at points adjacent the greatest horizontal dimension thereof; at least three straight column members having their lower ends equally spaced around and from said center line produced below said shell, said members converging from the supported ends thereof toward said shell, with their upper ends secured

4

to said post within said shell and with their longitudinal axes intersecting one another and said vertical center line at the point of theoretical application along said center line of the resultant of the horizontal forces acting on said shell so that there is no induced bending in said column members, due to the horizontal load on the tank.

2. An elevated tank and a tower support therefor, comprising a tank shell symmetrical about its vertical axis; a hollow post located within said shell, and surrounding such vertical axis; a plurality of frames radiating from, and equally spaced around, such vertical axis, and rigidly secured to said post and to said shell at regions intermediate the upper and lower ends of said shell, and adjacent the greatest horizontal dimension thereof; and at least three straight column members constituting a tower support for said tank, said column members having their supported ends equally spaced around and from such vertical axis projected to the ground, and converging upwardly from the supported ends thereof toward said tank, with each such member extending through said shell and secured to said post, and so arranged that their longitudinal axes intersect one another and the vertical axis of said shell at the point of application along such vertical axis of the resultant of the horizontal forces acting on said tank.

3. An elevated tank and the tower support therefor, comprising a tank shell substantially symmetrical about its vertical axis; a central post located within said shell, with the axis thereof substantially coincident with such vertical axis; and with the upper end thereof free from the upper portion of said shell; a series of frames radially arranged relatively to said vertical axis and substantially equally spaced around said post, each such frame being secured to said post at least at two points along the length thereof, and being secured to the interior of said shell in a region intermediate the upper and lower ends thereof and of maximum horizontal dimension, whereby the upper portion of said shell is free to expand and contract independently of said post and said frames; and at least three substantially straight column members having their ground-supported ends substantially equally spaced around and from the vertical axis of said shell projected to the ground, said column members converging from their supports upwardly toward said shell, with each such column member projecting through said shell and secured to said post within said shell, and equally spaced around the surface of said post, said members being so positioned with relation to each other and said shell, and so inclined with relation to the vertical axis of said shell, that the longitudinal axes thereof intersect each other and such vertical axis at the theoretical point of application along said vertical axis of the horizontal forces acting on said tank.

4. An elevated tank and support therefor, comprising an integral structure including a tank shell substantially symmetrical about its vertical axis; a hollow post surrounding the vertical axis of said shell and substantially concentric therewith and projecting upwardly toward the upper end of said shell, but with the upper end thereof spaced from and free of the upper portion of said shell; a series of frames located wholly within said shell, extending radially from said post, with the frames of the series substantially equally spaced around said

post, and with each such frame secured to said post and secured to said shell substantially midway between the upper and lower ends thereof and at a region of greatest internal dimension of said shell, whereby the intermediate portion of said shell is rigidly secured to said post and the upper portion of said shell is free to expand and contract independently of said post and said frames; at least three column members constituting a tower support for said tank, with the supported ends of said members equally spaced around and from the vertical axis of said shell produced below said shell, said column members converging upwardly from the supported ends thereof, with the upper end thereof rigidly secured to said post and equally spaced around the surface thereof, said column members being so positioned with relation to each other and to said post that the vertical axes thereof, when extended beyond said members, intersect with each other and with the vertical axis of said shell at the theoretical point of application along said vertical axis of the resultant of the horizontal forces acting on said shell.

5. An elevated tank and support therefor, comprising an integral structure including a spherical shell; a center post with the axis thereof substantially coincident with the vertical diameter of said shell, with the upper end of said post spaced from and free of said shell; a series of frames located within said shell, with the frames thereof extending radially relatively to said vertical diameter, and equally spaced around said post, and with each such frame secured to said post at spaced points along the length thereof and secured to the interior of said shell at points adjacent horizontal diameters thereof, whereby the upper portion of said shell is free to expand and contract independently of said post and said frames; at least three column support members constituting a tower support for said tank, said column members being equally spaced around and from the vertical axis of said shell produced below said shell and converging upwardly from their supported ends toward said post, with each such member extending through said shell and secured to said post at points within said shell and below the horizontal diameter thereof, said column members being so positioned with relation to said post and the vertical diameter of said shell, that the longi-

tudinal axes thereof, when extended beyond such members, intersect each other and the vertical diameter of said shell at the center of said shell.

6. A structure as defined in claim 5, in which 5 the frames are secured to said center post adjacent the upper end thereof and are almost wholly located in the lower portion of said shell.
7. A structure as defined in claim 5, wherein 10 said frames are located almost wholly in the lower portion of said shell.
8. An elevated tank and support therefor, comprising an integral structure including a substantially spherical shell; a hollow center post surrounding the vertical diameter of said shell and located co-axially therewith, with the upper end thereof spaced from and free of said shell; rigid means securing said post to said shell at points around such shell adjacent the horizontal diameter thereof, whereby the upper 15 portion of said shell is free to expand and contract independently of said post and said rigid means; at least three straight column members for support of said tank, said members being equally spaced around and from the vertical axis 20 of said shell produced below said shell, and converging upwardly from their supported ends toward said post, with each such member extending through said shell and secured to said post at points within said shell, said column members being so positioned with relation to each other, said post and the vertical axis of said shell, that the longitudinal axes thereof, when 25 extended beyond said members, intersect each other and the vertical diameter of said shell at a point substantially coincident with the center of said shell, whereby horizontal forces, acting on said shell, induce axial stresses only in said column members.

HARRY E. LINDBERG.
